COMPRESSOR UNIT CONSTRUCTION

Maxwell R. Karge, Brockport, N. Y.

Application April 16, 1932, Serial No. 605,682

7 Claims. (Cl. 230—212)

This invention relates to the construction of refrigerating units and its various component parts and the invention has for one of its objects to provide a construction for such units in which the compressor and condenser are built up from interchangeable parts.

Another object of the invention is to so construct most of the individual parts of the refrigerating unit that they may be used to build up units of different refrigerating capacity.

Another object of the invention is to provide the compressor cylinder with a novel form of valve which increases the efficiency of the compressor and makes its operation practically noiseless.

Another object of this invention is to build up a compressor unit in such a manner that the several parts thereof may be fastened together with a suitable packing between them which permits sufficient adjustment between the several parts so as to bring about a perfect alignment between them when these parts are fastened together.

Another object of this invention is to build up the condenser unit in such a manner that its heads provide a perfect base for the condenser as well as supporting members for the compressor and the motor drive thereof.

Another object of this invention is to provide the condenser with rectangularly shaped heads so that angle iron members can be used to connect them and form a rigid base on which the compressor unit is mounted above the condenser.

Another object of this invention is to so construct the cylinder assembly of the compressor that the clearance between the piston and the safety head of the cylinder may be varied.

Another object of this invention is to provide the compressor with a cylinder having a combined cylinder head and water jacket unit independent of the cylinder proper.

All these and other objects of this invention will become more readily apparent from the detailed description of the invention, reference being had to the accompanying drawings in which

Figure 1 is a side elevation of a refrigerating unit built up of interchangeable parts, with parts of the condenser of the unit illustrated in section.

Figure 2 is a vertical cross section of the condenser, the section being taken on the line 2x—2x of Figure 1.

Figure 3 is an enlarged end elevation of the condenser and a vertical cross section of the compressor mounted thereon.

Figure 4 is a horizontal sectional view of the cylinder of the compressor, the section being taken on the line 4x—4x of Figure 3.

Figure 5 is a vertical sectional view of the crank case of the compressor, the section being taken on the line 5x—5x of Figure 3.

Figure 6 is an enlarged vertical sectional view of the upper portion of the cylinder of the compressor illustrating the novel form of valve provided therein.

Figure 7 is a detail perspective view of the reed valve of the compressor.

Figure 8 is a side elevation of a two cylinder compressor built up of interchangeable parts.

In the several figures of the drawings like reference numerals indicate like parts.

The refrigerating unit forming the subject matter of my present invention comprises the compressor 1, the condenser 2, the trap 3 in the pipe line connecting the compressor with the condenser 75 and the driving motor 4 mounted on top of the condenser 2 and connected by a belt 5 with the pulley fly wheel 6 of the compressor 1.

Both the compressor and the condenser are mostly built up of parts which are interchangeable and so constructed that they may be used in building up units of different capacities. The compressor illustrated as part of the refrigerating unit is provided with a crank case made up of the cylindrical body which has its open ends finished off into the cylindrical flanges 7 and 8. These flanges are adapted to engage into the annular grooves 9 and 10 provided on the inside of the rectangular bearing blocks or ends 11 and 12 respectively.

In the bearing blocks are provided the 85 bearings 13 and 14 respectively which are located so as to be in line with each other when the cylindrical flanges 7 and 8 of the cylindrical body of the crank case are nested into the annular grooves 11 and 12 of the bearing blocks. The crank shaft 95 15 is suspended between bearings of the bearing blocks before the bearing blocks are fastened together against the cylindrical body of the crank case. The bearing blocks are fastened against the crank case by the four tie bolts 16, 17, 18 and 100 19 which pass thru suitable holes in the corners of the bearing blocks on the outside of the cylindrical section of the crank case and nuts 20 are threaded on the ends of the bolts to draw the blocks toward each other against the cylindrical body of the crank case.

A suitable yielding packing is placed into the annular grooves of the bearing blocks to provide an oil proof joint therein. In drawing the bearing blocks together the nuts 20 are alternately tightened so as to keep the bearing blocks toward each other against the cylindrical body of the crank case.

105 110

ings in line with each other which is true as long as the crank shaft can be rotated and does not bind in the bearings. The yielding packing between the bearing blocks and the crank case make this possible because it permits a slight angular adjustment of the bearing blocks on the crank case when they are fastened thereto by the tie bolts 16 to 19 inclusive.

10 The cylinder 21 of the compressor comprises a sleeve member which has its ends reduced to provide the annular shoulder 22 near the bottom thereof and the annular shoulder 23 near the top thereof. The reduced bottom portion of the cylinder is adapted to telescope into the crank case opening 24 and the shoulder 22 thereof rests on the flange 25 which surrounds this opening. A suitable yielding packing is placed between the shoulder 22 and the flange 25 to provide an oil tight joint between them after the cylinder is firmly anchored to the crank case.

15 The cylinder head 26 is telescoped over the reduced top of the cylinder 21 with the annular shoulder 23 thereof engaging the shoulder 27 provided in the cylinder head 26 and a suitable packing located between them. The cylinder head has the water jacket 28 provided therein which is closed at the top and open at the bottom. The open bottom of this jacket is closed by the circular flange 29 which is clamped against the open bottom with a suitable yielding packing between them.

20 The cylinder 21 is anchored to the crank case 6, while the cylinder head 26 is at the same time clamped in place on the cylinder by means of the tie bolts 30 and 31 which are threaded with one end into the top of the cylindrical body 6 of the crank case and project thru openings in the cover flange 29, the water jacket 28 and the top of the cylinder head to have the nuts 32 threaded to the projecting ends thereof. These nuts, when tightened against the cylinder head, draw the cylinder head down onto the top of the cylinder 21, and the cylinder 21 down onto the crank case 6 to firmly anchor the cylinder to the crank case and the cylinder head to the cylinder.

25 The yielding packing between the bottom of the cylinder and the crank case and the yielding packing between the top of the cylinder and the cylinder head allow these parts to perfectly align themselves with relation to each other when held together and by properly tightening the nuts 32 on the tie rods 30 the cylinder may be brought in perfect rectangular alignment with the crank shaft mounted in the crank case.

30 The packing between the bottom of the cylinder and the crank case permits a vertical adjustment of the cylinder on the crank case. Thus by decreasing the thickness of this packing the length of the cylinder is shortened and the clearance between the piston and safety head reduced. To increase this clearance the thickness of the packing is increased to lengthen the cylinder.

35 Additional nuts 32A are threaded intermediate of the tie rods 30 and 31 below the circular cover flange 29 which, when threaded up against this flange, clamps the flange over the open end of the water jacket and seal the jacket.

40 This built up construction has the advantage of using interchangeable parts which can be manufactured in quantities in the most efficient manner and when one of them becomes defective due to the wear or breakage, it can be replaced by a duplicate. A further advantage of this construction lies in the fact that the parts may be taken apart and cleaned periodically in order to keep

the operation of the compressor at a high efficiency.

45 For the purpose of making the operation of the compressor practically noiseless and increasing the operating efficiency thereof, the spring pressed disc valve 34 located within the cylinder head 26 at the end of the cylinder 21, is provided with a supplementary metal reed valve 33. This reed valve is normally flexed convex as illustrated in perspective in Figure 7 and is located over the valve ports 35. One end of the reed valve is provided with a rectangular hole 36 thru which passes the stud 37 to hold the reed valve lined up with the valve ports. Surrounding the stud 37 and interposed between the bottom of the head 38 thereof and the top of the reed valve 35, is the expansion spring 39 which normally forces one end of the reed valve down onto the top of the disc valve and assists the pressure of the gases above the valve disc in holding the reed valve 50 over the valve ports to normally keep them closed thereby. The fact that the reed valve is normally flexed convex prevents the pressure exerted on top of the reed from flexing it into a concaved shape which would keep the valve ports partly open. To prevent the reed valve from bending beyond its elastic limit at the point where it is held in place by the spring 39 when it is forced away from the valve ports by the pressure of the gases forced against it by the piston 40, a stop 55 pin 41 is mounted on top near the outer end of the reed valve. This stop pin extends upwardly and laterally toward the head 38 of the stud 37. The space between the end of this stop pin and the side of the head 38 determines the distance 60 the reed valve can flex to open the valve ports before it is held against further flexing by the contact of the stop pin with the side of the head 38. The amount of flexing allowed by the stop pin is such that it will not bend the spring beyond 65 its elastic limit or cause a crystallization of the spring at its bending point so that no matter how often the valve is flexed there is no danger of breaking it.

70 In the normal operation of the compressor in which only gases are compressed against the disc valve 32, these gases are forced thru the valve ports 34 and 35 and flex the reed valve angularly to admit the gases into the cylinder head above the disc valve 32. In the normal operation of the compressor the operation of the reed valve is thus sufficient for the compression of the gases and as the reed valve is very light in weight its opening and closing cannot be heard. During the operation of the compressor it happens that the gases contain a higher amount of moisture than usual. In such a case the reed valve must open a greater amount to allow the moisture to pass therethru with the gases. For this reason the end of the reed valve, instead of being rigidly anchored to the disc valve, is held by means of the spring 39. When therefore moisture is forced thru the valve ports, the reed valve is raised bodily against the pressure of the spring 39 and is reseated again by the spring as soon as the moisture has been forced thru the ports.

75 Sometimes it happens that a slug of liquid enters the cylinder and is being compressed by the piston. Such a liquid of course will not pass thru the valve ports and when forced against the underside of the disc valve will lift the disc valve itself against the pressure of the spring 43 which is located in the cylinder head and rests on top of the disc valve. The disc valve is thus operated only in the case where liquid is being compressed.

5 by the piston and this happens only occasionally. During ninety per cent of the operation of the compressor the normal operation of the reed valve is sufficient to force the gases into the circulating system, and when moisture is present in the gases, the operation of the reed valve, as governed by the expansion spring 39, will take care of the passing of the gases thru the valve ports in the disc valve. The disc valve may be made of steel but it has been found in practice that an aluminum valve may be used and this will deaden the sound of the contact of the valve with the end of the cylinder during its operation.

10 The condenser used in the refrigerating unit 15 as illustrated in Figure 1 is also built up of interchangeable members and comprises the cylinder 45, the ends of which project into the annular 20 grooves 46 and 47 of the rectangular heads 48 and 49 respectively. These heads are drawn 25 against the ends of the cylinder by the tie rods 50, 51, 52 and 53 by means of suitable nuts 50A, a suitable packing being provided in the annular 30 grooves to provide a tight joint between the cylinder and the heads thereof.

25 The cooling tubes 54 pass thru the cylinder 46 and its heads 48 and 49 and are held in place in the heads by means of the bushings 55 which are threaded to the ends of the cooling tubes and project into pockets which surround the ends of 30 the cooling tubes and contain a packing which is compressed when the bushings are tightened on the tubes.

35 Held clamped to the outside of the heads 48 and 49 are the auxiliary heads 56 and 57 respectively. These heads are drawn together against the heads 48 and 49 with a suitable packing between them by means of the tie rods 58 which pass thru the center of the cooling tubes. The 40 passage of the condensing water thru the cooling tube is thus restricted by the tie rods but the cooling efficiency of the amount of water which passes therethru is brought to a maximum by keeping the condensing water in contact with the inside periphery of the cooling tubes. Nuts 59 45 are threaded to the ends of the tie rods to draw the auxiliary heads against the heads proper and provide a tight joint between them.

50 The inside of the auxiliary heads is divided into compartments and auxiliary head 56 is provided with the partitions 60 and 61. An inlet 62 and an outlet 63 is also provided in this head and the cooling water enters the inlet 62 and due to the partition 60 passes thru the bottom 55 cooling tube into the inside of the auxiliary head 57. This head has but one partition 64 in the middle of it so that the cooling water entering the lower half of the auxiliary head is directed back to the first auxiliary head thru the lower two of the central cooling tubes. The condensing water thus reenters the first auxiliary head 60 above the partition 60 and is directed back to the second auxiliary head thru the upper two of the central cooling tubes. This brings the condensing water above the central partition of the auxiliary head 57 from where it flows back to the 65 upper compartment of the first auxiliary head thru the upper cooling tube and then out of this auxiliary head thru the pipe 65 into the water jacket of the compressor 1.

70 On top of the condenser on a suitable supporting plate 66 is mounted the base 67 of the driving motor 4 and this motor, as above described, drives the compressor by means of the belt 5.

75 The compressor is connected with the cylinder

45 by means of a pipe line 68 in which the trap 69 is located. This trap comprises a tubular member which is connected to the pipe line by the nipples 70 and 71. In the tubular member is mounted the stand pipe 72 which forms a continuation of the portion of the pipe line leading from the trap so that all gases have to pass thru this stand pipe in their passage to the condenser. In the top of the stand pipe 72 are provided one or more inlets 73 and on top of the stand pipe is mounted a cap 74 with a flange 75 extending to within a short distance of the inside periphery of the tubular member. Any oil entering the trap is thus forced against the inner wall of the trap and collects in the bottom of the trap while the gases are free to pass around the cap 74 and its flange 75 and enter directly into the inlet 73 of the stand pipe 72. In the bottom of the condenser is provided the outlet 76 to which is connected the cooling system fed by the refrigerating unit. The return from the cooling system is connected to the inlet 77 in the side of the cylinder of the compressor 1.

80 In Figure 8, I have illustrated the manner in which a two cylinder compressor is built up from the interchangeable parts. In this case a longer central cylindrical body 80 is used for the crank case, while a double cylinder head 81 is mounted over the two cylinders. The cylinder head and cylinders are fastened together and anchored to 85 the crank case by means of the three tie bolts 82, 83 and 84. Compressors with three or more cylinders may be built up in the same manner as the two cylinder compressor.

90 The rectangular heads 48 and 49 of the condenser provide a perfect base for the condenser at each end thereof and at the same time serve as supporting members for the compressor and motor drive. For this latter purpose the heads have the channel member 70 fastened thereto in 95 such a manner that the sides of this member embrace the upper portion of the heads and provide an extremely rigid and strong connection between them on which the compressor and motor drive is mounted.

100 I claim:

1. In a compressor construction the combination of a crank case having an opening therein, a cylinder having one end thereof nested into said opening, a cylinder head, a water jacket surrounding said cylinder head, said cylinder head with its water jacket being telescoped over the top of said cylinder, and tie bolts anchored in said crank case and passing thru said water jacket to simultaneously fasten said cylinder head to said 110 cylinder and said cylinder to said crank casing.

115 2. In a compressor construction the combination of a crank case having an opening therein, a cylinder having one end thereof nested into said opening, a cylinder head telescoped over the top of said cylinder, and tie bolts anchored in said crank case and passing thru said cylinder head to simultaneously fasten said cylinder head to said cylinder and said cylinder to said crank casing, a water jacket formed in said cylinder head 120 with one end open and the other closed, a cover for the open end and means carried by said tie rods to clamp said cover over the open end of said water jacket.

130 3. In a compressor construction the combination of a crank case comprising a central hollow member, cylindrical flanges formed on the ends of said hollow member, heads having annular grooves provided on the inside thereof to have 135 said cylindrical flanges nest into said grooves, 140

145

150

- bearings formed in said heads and tie bolts extending from one of said heads to the other thereof to fasten said heads against said hollow member with the cylindrical flanges engaging into said annular grooves and with said bearings in line with each other.
4. In a compressor the combination of a cylinder, a combined cylinder head and water jacket telescoped over the end of said cylinder to extend the top of said cylinder and surround a portion of it with said water jacket and a cover for closing said water jacket.
5. In a compressor the combination of a cylinder, a combined cylinder head and water jacket telescoped over the end of said cylinder to extend the top of said cylinder, said water jacket being open at the bottom and closed at the top, a crank case for supporting said cylinder and a pair of tie bolts anchored in said crank case and passing thru said cylinder head to fasten said cylinder head to said cylinder and said cylinder to said crank case, a cover for the open bottom of said water jacket, said tie bolts passing thru said cover and independent means carried by said tie bolts 25 to clamp said cover onto the open bottom of said water jacket.
6. In a compressor construction the combination of a crank case comprising an open ended shell having an opening in the wall thereof, a cylinder telescopically mounted in said opening, a head at each end of said shell, each head having a bearing therein, tie bolts connecting said heads and drawing said heads against the open ends of said shell with the bearings in said heads in line with each other and substantially in line with the center of said shell.
7. In a compressor construction the combination of a crank case comprising an open ended shell having an opening in the wall thereof, a cylinder telescopically mounted in said opening, a head at each end of said shell, each head having a bearing therein, tie bolts connecting said heads and drawing said heads against the open ends of said shell with the bearings in said heads in line with each other and substantially in line with the center of said shell, each of said heads having a portion of its edges straight, said tie bolts operating to hold said heads with their straight edges parallel to each other to provide a base for the support of said shell between them.
